AUTOMATIC CHARGE HEATING CONTROL FOR INTERNAL COMBUSTION ENGINES

Filed Oct. 23, 1919

FIG. 1.

FIG. 2.

FIG. 3.

Inventor

D. P. Molony

Attorney

UNITED STATES PATENT OFFICE.

DONALD PLUMMER MOLONY, OF FLINT, MICHIGAN, ASSIGNOR TO MARVEL CAR-BURETER COMPANY, OF FLINT, MICHIGAN, A CORPORATION OF INDIANA.

AUTOMATIC CHARGE-HEATING CONTROL FOR INTERNAL-COMBUSTION ENGINES.

Application filed October 23, 1918. Serial No. 332,702.

This invention relates to certain new and useful improvements in heating means for heating the explosive charge for internal combustion engines, the object being to provide a device by means of which the application of heat on the in-going gases is controlled by the exhaust, so that the proper amount of heat will be applied at all speeds of the engine.

Another object of my invention is to provide a device which can be readily applied to any of the well known type of charge forming devices, now in use, the construction being such that it is only necessary to provide a heating chamber having an inlet provided with a valve controlled by the exhaust gas pressure in the exhaust line.

With these objects in view, the invention consists in the novel features of construction, combination and arrangement of parts, hereinafter fully described and pointed out in the claims.

In the drawings forming a part of this specification:

Figure 1 is a side elevation of an internal combustion engine, partly in section showing the application of my improved construction of heat control, and

Figure 2 is a similar view showing the carbureter provided with a heating chamber for heating the explosive charge.

Figure 3 is a perspective view of the valve.

In Figure 1 of the drawing I have shown an internal combustion engine 1, provided with an intake manifold 2, to which is connected the carbureter 3, forming the charge forming device, and the particular construction of carbureter forms no part of this invention. The engine is provided with the usual exhaust pipe 4, which extends to the muffler, not shown, the above description being given so that the application of my improved construction of heat control can be readily understood.

In carrying out my invention, I provide a heating chamber 5, surrounding a portion of the manifold 2, said chamber being connected by inlet pipe 6, with the exhaust pipe 4, which is provided with a pivoted valve 7, for controlling the admission of exhaust gases. The heating chamber is provided with an outlet pipe 8, connected to the exhaust line pipe 4, so that when the valve is in opened position, the exhaust gases can pass into the heating chamber, in order to

apply heat to the manifold, whereby the explosive charge will be heated in its passage to the engine.

In order to control the heating medium which is applied through the heating chamber, I provide a pressure chamber 9, in which is mounted a plunger 10, having a plunger rod 11 working through one end of the chamber 9, as clearly shown, said plunger being connected to the valve operating arm 12 by a link 13, so that as the plunger raises and lowers, the position of the valve will be shifted in order to control the inlet of the heating chamber. A coil spring 14, is arranged under the plunger within the pressure chamber 9, and the ends of the chamber 9, are connected to the exhaust line pipe 4, by pipes 15 and 16, whereby the valve is actuated through the medium of the plunger by the amount of exhaust gas pressure in the exhaust line.

In Figure 2 of the drawing, I show a similar construction with the exception that the carbureter 3' is provided with a heat chamber 5', so that the application of heat will be around the mixing chamber. In both constructions the valve 7, is carried by a valve stem 7', which is provided with a pin 17 adapted to be engaged by the shoulder of a collar 18, loosely mounted thereon, said collar having an arm 19 extending therefrom, to which is connected operating means 20 controlled from the dash, so that the valve can be held open in warming up the engine, and while I have shown a particular construction for accomplishing this result, I do not wish to limit myself to the details shown, as other means could be employed for holding the valve open, without departing from the spirit of my invention. I have also shown a particular construction for automatically controlling the position of the valve by the exhaust gas pressure, but I do not wish to limit myself to any details of construction as my invention consists broadly in automatically controlling the heating medium applied for the purpose of heating the charge drawn into the engine by the amount of the exhaust gas pressure in the exhaust line, and I am aware that other means could be employed for accomplishing this result without departing from the spirit of my invention.

From the foregoing description it will be seen that I have provided an internal com-

bustion engine with automatic means for controlling the application of the heating medium employed for heating the ingoing gases in connection with manually operated means for resisting the automatic means to enable the engine to which the device is attached to be readily warmed up by allowing the gases to pass directly to the heating chamber. It will also be seen that the construction of valve is such that the same forms a deflector for causing the gases to pass into the inlet pipe of the heating chamber.

What I claim is:

15 1. The combination with an internal combustion engine having an intake and exhaust pipe, a heating chamber for heating the charge passing through the intake, said heating chamber having an inlet and outlet connected to the exhaust pipe, a valve for controlling the intake of said chamber, means actuated by the velocity of exhaust gas in said exhaust pipe for adjusting the position of said valve, and manually operated means for holding said valve in a predetermined position.

20 2. An internal combustion engine having an exhaust pipe, intake manifold and carbureter connected thereto, a heater arranged to heat the charge in its passage from the carbureter to the engine, means for controlling the admission of exhaust gases to said heater and means located outside of the exhaust pipe actuated by the velocity of the 25 heating fluid for actuating said heating fluid controlling means.

30 3. An internal combustion engine having an exhaust pipe, intake manifold and carbureter connected thereto, a heater arranged to heat the charge in its passage from the carbureter to the engine, a pressure chamber in communication with the exhaust pipe, a plunger mounted in said chamber, and means actuated by said plunger for controlling the admission of heating fluid to 35 said heater.

40 4. An internal combustion engine having

an exhaust pipe, intake manifold and carbureter connected thereto, a heater in communication with said exhaust pipe for heating the charge in its passage from the carbureter to the engine, a valve for controlling the admission of heating fluid to said heater, a pressure chamber in communication with said exhaust pipe, and a plunger mounted in said pressure chamber for operating said valve.

45 5. An internal combustion engine having an exhaust pipe, intake manifold and carbureter connected thereto, a heater arranged to heat the charge in its passage from the carbureter to the engine, a pressure chamber in communication with said exhaust pipe, a plunger in said chamber, and means actuated by the gas pressure in said chamber, 60 for controlling the admission of heating fluid to said heater.

6. An internal combustion engine having an exhaust pipe, intake manifold and carbureter connected thereto, a heater arranged to heat the charge delivered to the engine, said heater being in communication with the exhaust pipe, a valve for controlling the admission of exhaust gases to said heater, a pressure chamber in communication with said exhaust pipe, and a plunger mounted in 70 said pressure chamber having a connection with said valve.

7. An internal combustion engine having an exhaust pipe, intake manifold and carbureter connected thereto, a heating chamber arranged to heat the charge in its passage from the carbureter to the engine, said heating chamber being in communication with the exhaust pipe, a valve for completely cutting off the heat chamber from the exhaust pipe and means located outside of the exhaust pipe and in communication with the exhaust pipe for actuating said valve by the velocity of the exhaust gases passing through said exhaust pipe.

In testimony whereof I hereunto affix my signature.

DONALD PLUMMER MOLONY.
